UNITED STATES PATENT OFFICE.

JOSEPH M. BELL, OF MOUNT GILEAD, OHIO.

SELF-SERVING TABLE.

1,142,480.

Specification of Letters Patent.

Patented June 8, 1915.

Application filed January 12, 1914. Serial No. 811,690.

To all whom it may concern:

Be it known that I, JOSEPH M. BELL, citizen of the United States, residing at Mount Gilead, in the county of Morrow and State of Ohio, have invented certain new and useful Improvements in Self-Serving Tables, of which the following is a specification, reference being had therein to the accompanying drawing.

10 This invention relates to self serving tables and has for its object the production of a simple and efficient means for supporting the rotating center in such a manner as to prevent the rotating center from tipping 15 from side to side.

Another object of the invention is the production of a simple and efficient means for 20 efficiently supporting the rotating center so as to allow the center of the table to easily be rotated when it is so desired.

With these and other objects in view this invention consists of certain novel combinations, constructions, and arrangements of parts as will be hereinafter fully described 25 and claimed.

In the accompanying drawing, Figure 1 is a side elevation of the table, portions thereof being broken away to show the interior construction thereof. Fig. 2 is a detail perspective of a portion of the primary section of the ball-bearing race. Fig. 3 is a detail perspective of the auxiliary portion of the ball-bearing race. Fig. 4 is a detail perspective of the central supporting pin for 30 the rotating center. Fig. 5 is an enlarged vertical section through the main supporting leg of the table showing the socket portion which is adapted to receive the lower end of 35 the supporting rod. Fig. 6 is a vertical section of an embodiment of the table supporting device.

By referring to the drawings it will be seen that 1 designates the base which is provided with a plurality of diverging arms 2 at its upper end. These arms 2 support a substantially ring shaped top 3, and within this ring shaped top 3 is mounted the rotating center 4 of the table.

The rotating center 4 of the table is provided with a socket portion 5 within which is placed a lining 6 for receiving the enlarged knob end 7 of the supporting rod 8. The knob 7 is provided with a smooth upper end so as to allow the free rotary movement 55 of the central portion 4 of the table upon the supporting rod 8. This supporting rod 8

has its lower end seated in a lining 9 which lining is supported in the pocket 10 formed in the leg 1 of the table. This lining 9 is provided with a circumferential flange 11 60 around its edge so as to facilitate the securing of the lining 9 to the leg 1 of the table.

The outer edge of the central portion 4 of the table carries the primary section of the ball-bearing race, which primary section 65 comprises a sheet metal body having a flat base portion 12, which base portion terminates in a vertically extending wall 13, the vertically extending wall 13 in turn terminating in a laterally extending bridge portion 14, and this bridge portion 14 carries an integrally secured convo-convex channel 15, which channel 15 constitutes a pocket or race for supporting the ball-bearings 16. The base 12 of the primary portion of the 70 ball-bearing race is secured to the under face of the central portion 4 of the table by means of screws 17.

An auxiliary section of the race is mounted in the pocket 18 formed upon the under 80 and inner periphery of the top 3 and comprises a vertically extending wall 19 terminating in a rolled bead portion 20 which rolled bead portion 20 in turn terminates in an inwardly extending lateral flange 21. 85 The vertical wall 19 is secured in the pocket 18 by means of screws 22 and as clearly illustrated in Fig. 1. The bead portion 20 is adapted to receive the balls 16 and it will, therefore, be seen that by means of the present ball-bearing connection of the central portion 4 and the top 3 an efficient means has 90 been produced for facilitating the easy rotation of the central portion of the table 4.

From the foregoing description it will be 95 further obvious that owing to the manner in which the ball-bearings 16 are placed under the inner edge of the cover 3, these ball-bearings will prevent the central portion 4 of the table from tipping from side to side, 100 thereby holding the central portion of the table against swinging movement and only allowing a free rotary movement upon the central supporting knob 7 of the supporting rod 8.

In Fig. 6 there is shown an embodiment of the invention wherein the leg or supporting standard 1' is provided with a plurality of diverging supporting arms 2', which supporting arms 2' support the top 3'. A central rotating portion 4' is mounted within the top 3' and is supported upon a support-

ing rod 5' having an enlarged knob 6'. This knob 6' is seated in a casing 7' similar to that as illustrated and described in Fig. 1. The supporting rod 5' is provided with a plurality of diverging arms 8' which arms support a ball-bearing race 9' within which is mounted the ball-bearings 10'. An auxiliary portion 11' is carried by the central portion 4' of the cover or top of the table so as to hold the ball-bearings 10' in their correct position.

From the foregoing description it will be seen that in the modified form or embodiment illustrated in Fig. 6 that the central portion 4' of the table may be efficiently supported so as to easily rotate to the desired position.

Having thus described the invention what is claimed as new, is:—

20 A table of the class described comprising a base, a plurality of diverging arms formed

upon the upper end of said base, an annular top carried thereby and provided with a rotating central portion, said top provided with a rabbet around the inner edge upon the under face thereof, a race plate carried within said rabbet, a metallic race plate provided with an inwardly extending flange secured to the under face of said rotating central portion, bearings interposed between said race plates, said central pocket having a central pocket formed in the under face thereof, a metallic lining thereupon, and a supporting knob fitting within said central pocket.

25 In testimony whereof I hereunto affix my signature in presence of two witnesses.

JOSEPH M. BELL.
